UNITED STATES PATENT OFFICE.

OTTO LAUBER, OF BREDENEY, GERMANY, ASSIGNOR TO FRIED. KRUPP AKTIEN-
GESELLSCHAFT, OF ESSEN-ON-THE-RUHR, GERMANY.

DETACHABLE SPADE FOR WHEELED GUN-CARRIAGES.

1,090,077.

Specification of Letters Patent. Patented Mar. 10, 1914.

Application filed June 18, 1913. Serial No. 774,429.

To all whom it may concern:

Be it known that I, OTTO LAUBER, residing at Bredeney, Germany, a subject of the Emperor of Germany, have invented a certain 5 new and useful Improvement in Detachable Spades for Wheeled Gun-Carriages, of which the following is a specification.

This invention relates to a detachable spade for wheeled gun carriages, and particularly for heavy artillery, and it resides 10 therein that the spade is provided with organs which permit of attaching the wheels and a pole to the spade so that it can be transported by itself.

15 One embodiment of the invention is shown in the accompanying drawings illustrating a wheeled gun carriage.

Figure 1 shows a side elevation of the trail with the spade, partly in section; Fig. 2 a 20 top plan view of Fig. 1; Fig. 3 is a side view of a detail of the spade; Fig. 4 a top plan view of Fig. 3; the following figures are in 25 smaller scale: Fig. 5 is a side elevation of the spade in traveling position; Fig. 6 is a right hand front view of Fig. 5; and Fig. 7 the trail and spade in position for attaching or detaching the spade.

The trail is constructed of two flasks A of L-shaped cross section. The ends of these 30 flasks are connected with each other by means of a shoe B. The spade C C¹ consists principally of a spade plate C and a compressing plate C¹. The plate C and the compressing plate C¹ are connected with 35 each other by means of reinforcing flanges c². On the under side of each flask A is situated a narrow claw a¹ which is intended to engage with the forward edge c³ of the compressing plate C¹, see Figs. 1 and 2. At 40 the rear end of the compressing plate C¹, a broad guiding piece D is secured, against which the surface b¹ of the shoe B impinges, when the spade C C¹ is attached to the trail end. Beside the claws a¹ are provided two 45 for connecting the spade with the trail end. Each of these clamps E are constructed to engage with a head e¹ in a groove d¹, see Fig. 1, of the guiding piece D and these 50 clamps have a pair of eyelets e² which are constructed to grip a rib b² of the shoe B and may be locked to this rib by means of a pin b³, see Fig. 2. Lastly the clamps E are provided with surfaces e³ which abut against 55 a surface b⁴ on the shoe B, see Fig. 1, when

the clamps E are in their working position as illustrated in Figs. 1 and 2 of the drawings.

The trail may be displaced laterally relative to the spade C C¹, by turning a pinion F mounted in bearings in the shoe B, which pinion is in mesh with a toothed rack d² of the guide piece D. The spade C C¹ carries two bearings G situated on the reinforcing flanges c², which bearings are intended for a 60 wheel axle H for the wheels J. The wheel axle H may be non-revolubly and non-displaceably locked to the bearings G, by means of keys h¹. The spade is furthermore provided with co-axially arranged sleeves c⁴ c⁵, 65 which serve to hold in place a curved pole K, see Figs. 5, 6 and 7. The pole K may be secured by a key k¹, see Fig. 5 in the sleeve c⁵, and carries at its other end a trail eye k² which is intended for engaging the limber 70 hook m¹ of a limber M.

When the spade C C¹ is to be detached from the trail and transported separate, the trail end, together with the spade is first to be raised by means of a windlass into the 75 position shown in Fig. 7, the wheel axle H is thereupon pushed into its bearings G and the wheels J placed on the wheel axle H. The pole K is then placed in the sleeves c⁴ c⁵ in the position indicated in Fig. 7, where- 80 in it is turned 90° relative to its position shown in Fig. 5. The pin b³ is thereupon removed and the spade detached from the trail end by pushing against the wheels J. Lastly the pole K is limbered up on the lim- 85 ber M, see Fig. 5, after it has been turned 90° and secured in the sleeve c⁵ by the key k¹.

To attach the transported spade on the trail end, the latter is first placed over a pit which has previously been dug out for receiving the spade, whereupon the trail end is raised from the ground by means of a windlass, so that the spade on turning the pole K 90° may be connected with the trail end. The parts then again will take their 95 relative positions in accordance with Fig. 7. How the spade is secured to the trail needs no further explanation. As soon as the spade has been attached to the trail, the wheels J are taken off the wheel axle H and 100 the latter as well as the pole K removed, whereupon the trail together with the spade is lowered by means of a windlass.

I claim:

1. A detachable spade for artillery car- 110

riages comprising means for securing the spade to the trail end, a wheel axle and traveling wheels for the same, bearings in said space for the wheel axle, and means for connecting the spade with a limber hook, whereby said spade is adapted to be transported separate.

2. A detachable spade for artillery carriages comprising means for securing the spade to the trail end, a wheel axle and traveling wheels for the same, transverse bearings in said spade for the wheel axle, and means for connecting the spade with a limber hook, whereby said spade is adapted to be transported separate.

3. A detachable spade for artillery carriages comprising means for securing the spade to the trail end, a wheel axle and traveling wheels for the same, transverse bearings in said spade for the wheel axle, a key for locking said wheel axle in position, and means for connecting the spade with a limber hook, whereby said spade is adapted to be transported separate.

4. A detachable spade for artillery carriages comprising means for securing the spade to the trail end, a wheel axle and traveling wheels for the same, bearings in said spade for the wheel axle, a pole having a trail eye for engaging the limber hook and sleeves in the spade for receiving said pole.

5. A detachable spade for artillery car-

riages comprising means for securing the spade to the trail end, a wheel axle and traveling wheels for the same, bearings in said spade for the wheel axle, a pole having a trail eye for engaging the limber hook and sleeves in the spade for receiving said pole, and means for securing said pole in a fixed position in said sleeves.

6. A detachable spade for artillery carriages comprising means for securing the spade to the trail end, a wheel axle and traveling wheels for the same, transverse bearings in said spade for the wheel axle, a curved pole having a trail eye for engaging the limber hook and sleeves in the spade for receiving said pole, and means for securing said pole in a fixed position in said sleeves, in which its concave side lies opposite the ground.

7. A detachable spade for artillery carriages comprising means securing the spade to the trail end, a wheel axle and traveling wheels for the same, bearings on said spade for the wheel axle, and means for connecting the spade with a pole, whereby said spade is adapted to be transported separate.

The foregoing specification signed at 60 Barmen, Germany, this 28th day of May, 1913.

OTTO LAUBER. [L. S.]
In presence of—
HELEN NUFER,
ALBERT NUFER.
